E. A. G. ROULSTONE, OF ROXBURY, MASSACHUSETTS.

Letters Patent No. 63,179, dated March 26, 1867.

IMPROVEMENT IN CARPET-BAGS.

The Schedule referred to in these Letters Patent and making part of the same:

TO ALL WHOM IT MAY CONCERN:

Be it known that I, E. A. G. ROULSTONE, of Roxbury, in the county of Norfolk, and State of Massachusetts, have invented an Improvement in Travelling-Bags; and I do hereby declare that the following, taken in connection with the drawings which accompany and form part of this specification, is a description of my invention sufficient to enable those skilled in the art to practise it.

The invention relates to the manner of constructing the frames of travelling-bags and applying them to the flexible bag-forming material, having particular reference to strengthening the frame at the corners thereof, and giving to said corners a neat appearance, and to simplifying the application of the frame to the flexible bag material.

The nature of the invention will be more clearly understood after description and examination of the drawings, in which A denotes a cross-section of a portion of a frame and body, made and connected in accordance with my invention; B an outer view of the corner; C a cross-section of the frame through the corner rivet. a denotes the angle frame, having the body-applying edge turned over, as seen at b. c denotes the flexible bag-forming material, which may be formed with or without a lining, as circumstances require. The edge to be fixed to the frame I first apply over one edge of a strip, d, (as seen at A,) preferably securing it to this strip by stitches passing through the strip and leather. This strip is of such width as to cause it to fit tightly between the bottom of the groove formed by the turned-over edge b of the frame and the inner surface or side wall f of said frame, and after applying the edge of the flexible material to the strip I press said strip into place, as seen at A, riveting it to the frame, if desirable, or forming a bead or projection from the surface f, just below the strip, to hold it in position. Then by drawing the material outwardly from the frame, in forming the bag, it will be seen that the flexible material is not only connected to the frame so as to be undetachable therefrom, by wear or strain, at any point along its length, but also that the bent-over edge of the frame imparts a finish at the line of connection between the body and frame.

In bag frames recently devised by myself and by others it has been proposed, and to some extent practised, to cut out the material where the corner is formed, so as to simplify the bending of the metal into a neat and finished corner. As this construction, however, weakens said corner, and this at a point on the frame most exposed to wear, I turn down the whole or part of the triangular piece g, made by cutting the slit h, and overlapping and riveting together the tail-pieces i. This triangular piece is turned down against the inner surface of the frame before the metal is bent to form the corner, and this bending sets the piece tightly against the said inner surface and holds it firmly thereto, thus reinforcing the frame at the corner by the goring piece made in slitting the metal to facilitate the formation of the corner.

I claim the manner of connecting the flexible bag material to the frame by means of the strip d and the frame groove b, the strip and cloth or leather being first united, and then connected to the frame, as herein set forth and described.

Also, the reinforcement of the corner, by leaving the goring piece g in the frame, and turning it down against and so as to form part of the wall piece f, as herein set forth and described.

E. A. G. ROULSTONE.
